UNITED STATES PATENT OFFICE.

HARRY M. PFLAGER, OF ST. LOUIS, MISSOURI, ASSIGNOR TO COMMONWEALTH STEEL COMPANY, OF GRANITE CITY, ILLINOIS, A CORPORATION OF NEW JERSEY.

ROCKER CENTERING DEVICE

Application filed October 31, 1927. Serial No. 229,906.

My invention relates to railway rolling stock and consists in a novel rocker bearing structure adapted particularly to be used as a part of the centering device on a railway truck whereby the truck bolster, or other member having horizontal movement relative to the truck, is lifted when the same moves laterally from its normal position and reference is made to Woodard Patent No. 1,060,222 as embodying a description of this general type of rocker bearing centering device.

One of the objects of my invention is to reduce the cost of installation and maintenance of such devices, and this object is attained by providing bearing elements on the rocker and on the rocker supporting portion of the truck, which elements are separate from the rocker and truck frame structure and are renewable. The use of such elements eliminates the necessity of machining the rocker and rocker bearings to the extent previously required and when the bearing elements are unduly worn, one or more may be replaced without replacing the rocker or the rocker carrying portion of the truck frame.

Another object of my invention is to provide a rocker mounting which may be adjusted to different positions to present new rocker supporting faces, thereby increasing the useful life of the device without any replacement in whole or in part.

In the accompanying drawings which illustrate a selected embodiment of my invention—

Figure 1 is a transverse vertical section through one-half of a locomotive truck equipped with my invention and is taken substantially on the line 1—1 of Figure 2.

Figure 2 is a longitudinal vertical section through the truck and is taken substantially on the line 2—2 of Figure 1, the equalizer bars and truck springs being omitted to more clearly illustrate my invention.

The truck illustrated is a four wheel pony truck but it will be understood that the invention is applicable to two wheel trucks of this type and to trailer trucks and elsewhere. The truck wheels 1, axles 2, journal boxes 3, pedestals 4, wheel pieces 5, equalizers 6, springs 7, tie bars 8, and bolster 9 may be of any desired construction and form no part of my present invention.

The wheel pieces 5 of the frame are connected by transom elements comprising vertical walls 10 and a transverse web 11 con-

necting the lower portions of walls 10. Web 11 is provided with one or more upstanding ribs 12, 13 and these ribs are adapted to cooperate with the adjacent wall 10 to mount suitable pins 14 which may be inserted through wall 10 from the outside of the latter and may be retained in position by the engagement of each pin head 15 by a removable bolt 16 which is detachably mounted in flanges 17 formed on the outer face of wall 10.

Rocker members 18 are mounted upon pins 14 and in the preferred form each rocker member comprises a pair of rockers located respectively on opposite sides of the transverse center line of the truck but interconnected by an integral portion 19. Each of these rockers is provided with a pair of concave recesses spaced along its base and each of these recesses is preferably lined with a relatively hard steel wear plate 20 preferably secured to the body of the rocker by spot-welding as indicated at W.

It is obvious that the above construction eliminates the necessity of machining semi-circular recesses on the truck frame or the provision of heavy machined bars which must be applied to the truck frame to seat the rocker. The construction also eliminates the formation of journals on the bases of the rockers, which journals must be machined in order to properly fit in their bearings.

Aside from the elimination of machining of rocker bearings for original installation, my device is advantageous because of the fact that the wear plates 20 may be renewed at intervals without renewing the rocker and the pins 14 may also be renewed at intervals without renewing any other part of the device.

The pin heads 15 may be made circular, in which case the pin 14 may rotate on its seat and the circumferential wear on pin would be evenly distributed but my preferred construction is to make the heads 15 rectangular or some other non-circular shape whereby the pins 14 will be held against rotation on their axes. With this arrangement the pins may be withdrawn at suitable intervals and given a half or less turn about their axes to present a new rocker supporting face.

In the construction shown the inner pin supporting rib 12 surrounds the inner end of the pin and an intermediate rib 13 engages the lower face only of the pin immediately below the pin engaging portion of the rocker. It

will be understood that this intermediate rib may be eliminated if desired or the entire surface of web 11 beneath the pin may be machined to seat the pin.

5. These and various other modifications in the details of my invention may be made without departing from the spirit thereof, and I contemplate the exclusive use of such variations in the structure as fall within the 10 scope of my claims.

I claim:

1. In a rocker bearing for a railway truck, an element on the truck frame, a rocker, a cylindrical pin applied to said element and 15 forming a bearing for said rocker, and means securing said pin to said element.

2. In a rocker bearing for a railway truck, an element on the truck frame, a rocker, and a renewable pin extending through said element and forming a bearing for said rocker. 20

3. In a rocker bearing for a railway truck, an element on the truck frame, a rocker, a cylindrical pin rotatably mounted on said element and forming a bearing for said 25 rocker, and means securing said pin to said element.

4. In a rocker bearing for a railway truck, an element on the truck frame, a rocker, a cylindrical pin rotatably mounted on said element and forming a bearing for said rocker, and means for holding said pin against 30 rotation in various positions.

5. In a rocker bearing for a railway truck, an element on the truck frame, a rocker having a concave recess, a renewable concave wear plate seated in said recess, and a renewable pin mounted on said element and supporting said rocker through said wear plate. 35

6. In a railway truck, a frame having spaced vertical members, a pin seated in said members, and a rocker having a recess in its base for mounting the rocker on said pin. 40

7. In a railway truck, a frame element having spaced vertical members, and a rocker supporting pin seated in said members, one of said members surrounding said pin and another of said members engaging only the underside of said pin. 45

8. In a railway truck, a frame element having spaced vertical members and a rocker supporting pin seated in said members and provided with a non-circular head, one of 50

said members surrounding said pin and another of said members engaging only the 55 underside of said pin, and a flange on one of said members for engaging the side of said head to prevent rotation of said pin.

9. In a railway truck, a frame element having spaced vertical members and a rocker 60 supporting headed pin seated in said members, a flange on one of said members extending past the side of said head, and an element detachably secured to said flange to engage the end of said head to prevent accidental removal of said pin from said members. 65

10. In a railway truck, a frame including a vertical transom wall, a horizontal web extending inwardly from the lower portion of 70 said wall, upstanding ribs on said web, and a rocker supporting pin inserted through said transom wall from the exterior face thereof and supported on said ribs, and means for retaining said pin in position. 75

11. In a railway truck, a frame including a vertical transom wall, a horizontal web extending inwardly from the lower portion of 80 said wall, an upstanding rib on said web spaced from said wall, and a pin inserted through said wall and rib and adapted to support a rocker bearing between them.

12. A railway centering device bearing member comprising a rocker having a recess and a renewable wear plate of relatively hard 85 material secured in said recess.

13. A railway centering device bearing member comprising a rocker having spaced recesses along its base and separate renewable plates of relatively hard material seated in 90 said recesses.

14. A railway centering device bearing member comprising a rocker element, and renewable wearing elements of curved contour attached to the base of said rocker element 95 and adapted to engage a supporting surface.

15. In a railway truck, a frame element having spaced vertical members and a rocker supporting pin seated in said members and provided with a non-circular head, and a 100 flange on one of said members for engaging the side of said head to prevent rotation of said pin.

In testimony whereof I hereunto affix my signature this 25th day of Oct., 1927.

H. M. PFLAGER.
